UNITED STATES PATENT OFFICE.

HARRY L. DUNCAN, OF RIDGEWOOD, NEW JERSEY.

INCANDESCENT PROJECTING LAMP.

Application filed June 30, 1921. Serial No. 481,449.

This invention relates especially to metallic filament incandescent lamps adapted for optical projecting purposes etc., and in which the incandescent metallic filament or 5 incandescent body in the form of a thin strip or sheet of tungsten, etc., which is preferably mounted in a nitrogen filled bulb or lamp body, may present a substantially continuous incandescent surface to the projecting apparatus. One or more diaphragm shields of refractory or infusible material are preferably connected with or mounted adjacent this incandescent strip, so that the restricted transmitting aperture of the diaphragm device definitely limits the active 10 illuminating portion of the incandescent strip so that a more definite and uniformly heated incandescent radiating surface is thus secured.

20 In the accompanying illustrative somewhat diagrammatic drawing,

Fig. 1 is a vertical section.

Fig. 2 is an enlarged vertical section through the filament and diaphragm.

25 Fig. 3 is a rear view thereof.

Fig. 4 is an enlarged section through a modified filament and diaphragm arrangement.

Fig. 5 is a rear view thereof; and

30 Fig. 6 is an enlarged section through still another arrangement.

The lamp may comprise the substantially spherical bulb or lamp body 78 of regular or special glass formed with the neck 19, 35 within which the glass or other support 20 is mounted so as to support the lead wires or other supports 12, 14 which may be fused into the closed end 21 as indicated in Fig. 1. This lamp bulb is preferably filled with 40 nitrogen or other suitable inert gas under the desired pressure, so that the incandescent metallic filament or incandescent body can be operated at high temperature and efficiency.

45 As is shown in greater detail in Figs. 2 and 3 the incandescent body or surface which is preferably substantially flat, may be formed of one or more strips or thin sheets of tungsten or other relatively infusible metal or material such as is used for incandescent lamp filaments, so as to form a substantially flat incandescent illuminating surface which may be three eighths of an 50 inch wide more or less and located in any suitable or desired part of the bulb. In the 55 arrangement shown in Fig. 3 the strip of

such thickness as to give the desired resistance and other properties under working conditions, may be formed with a transverse fold 2 within which may be located or arranged a tensioning stirrup 3 which may have a neck and connected eye 4 projecting through an opening in the folded strip. In this way the two ends 1 and 3 of the strip may form a substantially U-shaped incandescent body and preferably have their adjacent edges somewhat overlapping as indicated in Fig. 3, so that a substantially continuous incandescent surface is presented in the direction in which the projecting beam of light is transmitted. These strip ends may be connected in any suitable way to lead wires such as 12, 14 which may have their ends 7, 9 twisted or locked around the adjacent portions to form connecting or supporting stirrups to which the strip ends may be united or connected in any suitable way. These lead wires may in some cases support the diaphragm shield 6 adjacent the illuminating surface as by running these lead 60 wires through holes 11 in the connecting flange or portion 15 of the shield around which the wires may be bent sufficiently to give firm or substantially rigid connection therewith, and of course these lead wires 70 which may be of tungsten or other suitable material are preferably sufficiently heavy so as not to undesirably soften or bend under the working currents used. A similar connecting flange or portion 16 on the diaphragm shield may support the tensioning wires 18, which may have a ring or aligning portion engaging the eye 4 of the stirrup; and the ends 17, 22 of these wires may be brought around through holes in this flange, 80 and bent or secured so as to prevent loosening or withdrawal.

75 The diaphragm shield devices, which are preferably formed with a restricted transmitting aperture adjacent the incandescent illuminating surface and substantially parallel thereto, may be formed of any suitable refractory or relatively infusible material such for instance, as porcelain, pottery or the like which is preferably so constructed 90 and spaced with relation to the incandescent filament as not to become undesirably heated or incandescent, so that the projected light is substantially limited to the beam issuing through the transmission aperture 8 in the 95 diaphragm. For these reasons a generally circular or conical shape may be given to 100 105 110

this aperture, and in some cases the radiating ribs 30 may be formed on this adjacent side of the diaphragm so as to project beyond the edge as shown in Fig. 3 and promote the radiation of any transmitted heat and keep the diaphragm temperature down sufficiently. For this purpose the outer edge of the diaphragm may be somewhat thicker in many cases, and it is also advantageous to cut down light reflection from the outer side of the diaphragm by giving this surface 28 a ridged roughened or matt dark surface or finish as by rough grinding or sandblasting or by partially fusing or uniting roughened particles thereto, either before or after this vitreous or diaphragm is baked or formed.

Figs. 4 and 5 show another illustrative arrangement in which the incandescent body 31 may consist of a single thin strip or sheet of tungsten or other suitable high fusing metal. The ends of this strip, which may be a quarter to a half of an inch wide more or less, may be bent around and secured or united to the middle portions 32, 34 of the U-shaped lead wires 42, 44, which may be carried up through the neck of the bulb or lamp body in any suitable well known manner. The diaphragm shield 36 which may have a somewhat roughened or darkened exposed surface 37, may have the restricted transmitting aperture 38 smaller than and preferably substantially parallel to the incandescent illuminating surface 31, and this diaphragm may be supported in connection with the illuminating surface in any suitable way as by the connector wires 45, 48 hooked or looped around the lead wires and having bent ends such as 46 arranged in apertures 47 in the diaphragm. When these connector wires are made of resilient tungsten or the like, the diaphragm is securely supported in the desired position and a substantial tensioning action may be exerted on the incandescent strip or filament if desired.

Fig. 6 shows another illustrative arrangement in which similar lead wires such as 44 have their U-shaped or bent portions 32, 34 connected to the ends of the incandescent filament strip 31. The pottery or other refractory diaphragm 56 may be similarly supported as by the connector wires 45, so that as shown its aperture 52 may in some cases be still closer to the incandescent illuminating surface; and the diaphragm may be of double conical form at this point, having the conical surfaces 53, 57 while the more flatly conical surface 54 makes the outer edge 55 of the diaphragm somewhat thicker. In this and the other illustrated constructions, the diaphragm shield structure may be composite and may comprise a secondary diaphragm such as 59 of tungsten or other refractory metal or material, which may preferably have its transmitting aperture 60 of

somewhat smaller diameter than the primary diaphragm shield and spaced away therefrom, so as to provide for cooling convection currents between these parts. This secondary diaphragm may have an outer flaring 70 edge 61 and a roughened blackened exposed surface 62, this diaphragm being supported in any suitable way as by the connector wires or members 63 from the primary diaphragm 55. It is of course evident that the 75 relatively thick central portion of this secondary diaphragm which is exposed to the radiation of the incandescent surface can reflect and otherwise dissipate the heat fast enough so as to prevent its becoming undesirably hot or luminous. These diaphragm shield devices thus definitely localize or restrict the actively transmitting portions of the incandescent surface to parts that are substantially uniformly heated in producing the projecting beam of light; and in this way a more definitely localized and reliable illuminating surface can be secured than by coiled or similarly concentrated filament arrangements, and arc light conditions are 80 thus more nearly approached while at the same time focusing difficulties usual with arc lights are avoided.

This invention has been disclosed in connection with a number of illustrative embodiments, forms, proportions, elements, parts, shapes, materials, compositions, conditions, and methods of preparation, production and use, to the details of which disclosure the invention is not of course to be limited, since what is claimed as new and what is desired to be secured by Letters Patent is set forth in the appended claims.

What I claim is:—

1. In incandescent projecting lamps, an incandescent body comprising a thin flat strip of tungsten bent to form a substantially U-shaped conductor in substantially the same plane, and having the adjacent edges of the strip somewhat overlapping, lead wires connected to the ends of said strip and a wire tensioning device and connected stirrup arranged in the folded end of the strip opposite the lead wires, a nitrogen filled bulb in which said incandescent body is supported and a diaphragm shield supported in connection with said incandescent body and having adjacent and substantially parallel to the substantially flat surface of said incandescent body an aperture through which the useful illumination is transmitted, the outer surface of said diaphragm being rough to minimize light reflection therefrom.

2. In incandescent projecting lamps, an incandescent body comprising a thin flat strip of tungsten bent to form a substantially U-shaped conductor in substantially the same plane, lead wires connected to the ends of said strip and a tensioning device connected to the folded end of the strip opposite the

- lead wires, a nitrogen filled bulb in which said incandescent body is supported and a diaphragm shield supported in connection with said incandescent body and having adjacent the substantially flat surface of said incandescent body an aperture through which the useful illumination is transmitted.
3. In incandescent lamps, an incandescent body comprising a flat strip of high fusing metal having adjacent portions in substantially the same plane, and having the adjacent strip edges somewhat overlapping, lead wires connected to said strip, a bulb in which said incandescent body is supported and a diaphragm shield supported in connection with said incandescent body and having adjacent the substantially flat surface of said incandescent body an aperture smaller than said incandescent body through which the useful illumination is transmitted.
4. In incandescent lamps, an incandescent body comprising a flat strip of high fusing metal having adjacent portions in substantially the same plane, lead wires connected to said strip, a bulb in which said incandescent body is supported and a diaphragm shield having adjacent the substantially flat surface of said incandescent body an aperture smaller than said incandescent body through which the useful illumination is transmitted.
5. In incandescent projecting lamps, an incandescent body comprising a substantially flat surface of high fusing metal strip, connected lead wires, a bulb in which said incandescent body is supported and a plurality of separated diaphragm shields supported in connection with and adjacent said incandescent body and having a light transmitting aperture smaller than said incandescent body and substantially parallel thereto.
6. In incandescent projecting lamps, an incandescent body, a bulb in which said incandescent body is supported and a plurality of separated diaphragm shields supported in connection with and adjacent said incandescent body and having a light transmitting aperture smaller than said incandescent body.
7. In incandescent projecting lamps, an incandescent body comprising a substantially flat surface of tungsten strip, connected lead wires and tensioning devices, a lamp body in which said incandescent body is supported and a diaphragm shield having heat radiating projections and supported in connection with and adjacent said incandescent body and having a light transmitting aperture substantially parallel thereto, the outer surface of said diaphragm being darkened and roughened to minimize light reflection.
8. In incandescent projecting lamps, an incandescent body comprising a substantial- ly flat surface of tungsten strip, connected lead wires, a lamp body in which said incandescent body is supported and a dia- phragm shield having heat radiating pro- jections and supported adjacent said incandescent body and having a light trans- mitting aperture.
9. In incandescent lamps, an incandescent body comprising a substantially continuous flat surface of high fusing metal strip, connected lead wires, a lamp body in which said incandescent body is supported and a dia- phragm shield supported within said lamp body adjacent said incandescent body and having a substantially circular light trans- mitting aperture relatively smaller than said incandescent body and substantially parallel thereto.
10. In incandescent lamps, an incandescent body comprising a high fusing metal, connected lead wires, a lamp body in which said incandescent body is supported and a diaphragm shield supported adjacent said incandescent body and having a substan- tially circular light transmitting aperture relatively smaller than said incandescent body.
11. In incandescent projecting lamps, an incandescent body comprising a transmit- ting portion which appears substantially continuous when viewed from the direction of the useful light beam, a bulb in which said incandescent body is supported and a diaphragm shield supported in connection with and adjacent said incandescent body and having a light transmitting aperture smaller than said incandescent body and substantially parallel thereto.
12. In incandescent lamps, an incandescent body, a sealed bulb in which said incandescent body is supported and a diaphragm sup- ported in connection with and adjacent said incandescent body and having a light trans- mitting aperture relatively smaller than said incandescent body.
13. In incandescent electric lamps, an in- candescent body comprising a substantially continuous flat surface of high fusing metal, connected lead wires, a sealed lamp bulb in which said incandescent body is excentrically supported and a diaphragm shield sup- ported adjacent said incandescent body and having a light transmitting aperture rela- tively smaller than said incandescent body.
14. In incandescent electric lamps, a me- tallic incandescent body, a sealed lamp bulb in which said incandescent body is supported and a diaphragm supported adjacent said incandescent body and having a light trans- mitting aperture relatively smaller than said incandescent body.
15. In incandescent projecting lamps, an incandescent body comprising a thin flat strip of tungsten bent to form a substan- tialy U-shaped conductor in substantially the

same plane, and having the adjacent edges of the strip somewhat overlapping, lead wires connected to the ends of said strip and a wire tensioning device and connected stirrup arranged in the folded end of the strip opposite the lead wires.

16. In incandescent projecting lamps, an incandescent body comprising a thin flat strip of high fusing metal bent to form a substantially U-shaped conductor in which the substantially flat strip forming the adjacent arms of the U-shaped conductor are in substantially the same plane as the plane of the U, lead wires connected to the ends of said strip and a tensioning device connected

to the bent end of the strip opposite the lead wires.

17. In incandescent projecting lamps, an incandescent body comprising reflexly bent thin flat strip of high fusing metal bent to form adjacent conducting arms in which the flat strip is arranged with slightly overlapping edges when viewed in the projecting direction and is arranged in substantially the same plane as the strip arms, lead wires and tensioning means to hold said strip arms substantially in their extended position and maintain a substantially continuous incandescent surface in the projecting direction.

HARRY L. DUNCAN.
